LOOM FOR NARROW WEBS WITH LOCKED SELVAGES

Carl F. Libby, Stoughton, Mass., assignor to John D. Riordan, Hopkinton, and Gertrude C. Libby, Stoughton, Mass., as trustees

Application December 9, 1954, Serial No. 474,087

6 Claims. (Cl. 139—124)

This invention relates to narrow web looms of the type wherein the picks consist of loops of weft yarn projected alternately from opposite sides of the warp, the shed being changed every time a loop of weft is laid therein. In looms of this kind, the extremity of each loop projected through a shed is caught at the opposite side of the warp and projected through the end of the loop next previously projected in the same direction. In the resulting web, if a weft yarn breaks at any point, it ravelles easily, especially if it is a smooth yarn like rayon. In order to lock the selvages so as to make ravelling more difficult and less liable to result from the breaking of one of the weft yarns, one or more separate selvage yarns have been knitted in with the extremities of the weft loops, an example of this being shown and described in my Patent No. 2,492,051.

According to the present invention, a loom is provided with means whereby on each side of the warp, a selvage yarn is provided, a loop of which is thrust through the extremity of the weft loop projected from the other side. Then the next weft loop in course of being projected to the other side is first thrust through the selvage loop. This sequence is repeated each time a new weft loop is projected from the other side. A similar sequence of steps takes place at the other side of the warp so that in both selvages, each weft loop from the other side is locked by a selvage loop on the near side which selvage loop is in turn locked by the next weft loop projected from the near side to the other side of the warp. For successful operation of the loom it is essential that each of the loops mentioned be held open to receive the next loop which is to be thrust therethrough until the latter has actually entered the former, particularly in looms which are designed to operate at high speeds. Provisions are made for this requirement in the loom hereinafter described.

In the drawings,

Figure 1 is a plan view of narrow web loom mechanisms for forming locked selvages as described;

Figure 2 is a section on line 2—2 of Figure 1;

Figure 3 is a section on line 3—3 of Figure 1;

Figure 4 is a diagrammatic plan view showing some of the thread-handling members at one stage of a cycle of operation;

Figures 5, 6 and 7 are similar views showing the parts at later stages in the cycle;

Figure 8 is a section on the line 8—8 of Figure 4;

Figure 9 is a section on the line 9—9 of Figure 5;

Figure 10 is a section on the line 10—10 of Figure 9;

Figure 11 is a section on the line 11—11 of Figure 6; and

Figure 12 is a diagrammatic showing of the resulting fabric.

The drawings illustrate part of a narrow-web loom comprising the mechanism for laying the weft yarns in the shed and locking the loops with selvage yarns. In some of the figures of the drawing a fragment of the fabric which is being woven is shown, as well as the two weft

2

yarns and one of the selvage yarns, but the warp yarns forming the sheds are not shown, to avoid confusion of detail.

As shown, on a main frame 20 are mounted two weft laying fingers 22 and 24 which are pivoted at 26 and 28, respectively, for alternate reciprocation through the shed to lay loops of weft yarn therein. For the actuation of these weft-laying fingers, they are connected by respective links 30 and 32 to a longitudinally reciprocated bar 34 which extends transversely of the loom in a guide slot in the top of the frame 20. The bar 34 is connected by a pitman 36 (Figure 2) to a crank wheel 38 mounted on a vertical shaft 40. Also mounted on the shaft 40 are two eccentrics 42 and 44 for the actuation of other reciprocable members in timed relation with the movements of the fingers 22 and 24. The eccentric 42 has the usual eccentric strap and rod 46 connected to a crank arm 48 pivoted at 50. A radial arm 52 from the pivot 50 rocks with the arm 48. Mounted on the end of the arm 52 is an arcuate needle 54 arranged so that the arc of its curvature is concentric with the axis of the pivot 50. One end of the needle 54 is mounted on the arm 52. The other end is pointed and has an eye for thread near the point. The rock-arm 52 is operatively connected by suitable linkage including a rod 56 to a similar rock-arm 58 on the other side of the shed. An arcuate needle 60, similar to the needle 54, is mounted on the arm 58. The connecting linkage is such that the needles 54 and 60 rock about their pivots in opposite phase, the pointed ends moving in arcuate paths which are almost tangent to the edges of the fabric at the fell thereof.

The eccentric 44 has a strap and rod 62 connected to an arm 64 rockable about a pivot 66. A hook 68 rocks with the arm 64 about this pivot and is operatively connected to a similar hook 70 on the other side of the shed by linkage including a rod 72. On each side of the shed, therefore, is a finger, a needle and a hook, all these members being driven by connections with the shaft 40 so that they all move in timed relation as hereinafter described.

A pair of thread guide members 74 and 76 are mounted on opposite sides of the shed. Each of these guides is an upright lever pivoted as at 78 near the lower end so that the upper end which has an eye therein is rocked forward and rearward to take up slack in the selvage yarns S, S' at the right moments, as hereinafter described, these yarns being drawn from suitable sources (not shown) through tension devices 79, one of which is shown in Figure 4. The levers 74 and 76 may be rocked by any convenient means such as cams 80 and 82 mounted on a countershaft 84. The latter is connected to the vertical shaft 40 bevel gears 86 so that these shafts rotate in unison. Power for driving these shafts may be had by gear wheels 88 which connect the shaft 84 with a power shaft 90 carrying a pulley 92 for a belt. The power shaft 90 is also connected by gearing 94 to a shaft 96 on which is mounted a revolving reed 98. This too must move in timed relation to all the other moving parts.

The interaction of the fingers, needles, hooks and tension members is illustrated in Figures 4 to 11. The portion of each of the fingers 22 and 24 which projects through the shed intermittently is arcuate, the curvature being concentric with the pivot about which the finger rocks. On the convex edge of this portion of each finger is a groove or channel 100 (Figure 11) in which a weft yarn freely slides to an eye in the tip of the finger. One weft yarn W is introduced into the shed from the left by the finger 22. The other weft yarn W' is introduced from the right by the finger 24. Figure 4 shows the finger 22 projected all the way through the shed with a loop of weft yarn W. The finger has a terminal nose 102 extending at an angle from the arcuate

portion to hold the loop of yarn W open for the insertion therethrough of a loop of selvage yarn S by the needle 60 to the right of the shed (Figures 4 and 8). When the pointed end of the needle 60 has carried the end of the loop of selvage yarn beyond the point of the hook 70, the latter is rocked to catch the loop of selvage yarn as illustrated in Figures 5 and 9. Each of the hooks 58 and 70 is formed with a deep channel 104 in the outer or convex edge of its bent portion which forms the hook. The channel 104 is large enough in cross-section to receive the end portion of one of the fingers 22 and 24. After the hook 70 has entered the loop of selvage yarn S carried by the needle 60, the needle is withdrawn, leaving the loop on the hook. The finger 22 also returns to the left. When it is clear of the shed, the shed changes and the finger 24 is projected through the new shed. As it starts through the shed its end portion rides in the channel 104 of the hook 70 and thus inserts a loop of the weft yarn W' through the loop of selvage yarn then held by the hook 70. As soon as the end of the finger 24 has passed through the loop on the hook 70, the hook is swung back to disengage itself from the selvage yarn. The slack take-up lever 76 thereupon swings forward to take up the slack in the loop of selvage yarn S which now passes around the finger 24 and the loop of weft yarn W' carried thereby. Meanwhile the finger 24 is rapidly projected through the shed and retracted therefrom, its loop of weft yarn W' being caught on the left-hand side of the shed by the needle 54. When the finger 24 is clear of the shed, the motion of the take-up lever toward the front of the machine pulls the loop of selvage yarn taut about the loop of weft yarn W' which has just been laid in the shed (Figure 7). The finger 22 is then projected through the next shed from the left to the position shown in Figure 4, thus completing a cycle of operations at the right of the shed. Similar cycles take place to the left of the shed when the finger 24 carries loops of the weft yarn W' beyond the left side of the shed to be caught by the needle 54 which carries another selvage yarn S' (not shown except in Figure 12).

In the resultant fabric, each loop of weft yarn projected through the shed is caught by a loop of selvage yarn at the further side of the shed, the selvage loop then being caught by the loop of the other weft yarn which is projected from the near side of the shed.

I claim:

1. In a narrow web loom having shed-forming means, two weft fingers reciprocable to project alternate loops of two weft yarns from opposite sides of the shed, a needle for a selvage yarn mounted on each side of said shed for reciprocatory movement in timed relation to the movements of the finger on the other side of the shed to project a loop of selvage yarn through the extremity of the weft loop projected through the shed by said finger, a hook mounted near and associated with each of said needles and reciprocable in timed relation with its corresponding needle to catch therefrom the loop of selvage yarn after it has been thrust through said weft loop and to hold said loop of selvage yarn open for the projection of the adjacent weft finger therethrough, and connected means for driving said fingers, needles and hooks.
2. Apparatus as in claim 1, and a reciprocable guide for each selvage yarn operated in timed relation to the movements of the corresponding hook to take up the slack in the loop of selvage yarn released by said hook.
3. Apparatus as in claim 1, each said needle comprising an arcuate shank with a pointed end and an eye near said end, a horizontal arm to which the other end of said shank is secured, and pivot means for reciprocating said arm about a vertical axis concentric with the curvature of said shank.
4. Apparatus as in claim 1, each said hook having trough-like cross-section at the end-portion thereof adapted to hold separated the sides of a loop of yarn caught on the hook.
5. Apparatus as in claim 1, each said finger having an elongated end portion adapted to extend from one side of the shed to the other, said end portion being arcuate with a thread channel in its convex side.
6. Apparatus as in claim 1, and means for tightening each loop of selvage yarn about one of said weft loops, said last-named means comprising a tension device for each said selvage yarn, and a reciprocable take-up lever having an eye through which the selvage yarn passes from its tension device to the corresponding needle.
